S. T. McLELLAN.

VALVE.

FILED APR. 1, 1921.

Inventor:
Samuel T. McLellan.

Samuel T. McLellan

Attorney.

UNITED STATES PATENT OFFICE.

SAMUEL T. McLELLAN, OF CHARLESTON, WEST VIRGINIA.

VALVE.

Application filed April 1, 1921. Serial No. 457,636.

To all whom it may concern:

Be it known that I, SAMUEL T. McLELLAN, a citizen of the United States, residing at Charleston, in the county of Kanawha, State 5 of West Virginia, have invented certain new and useful Improvements in Valves; and I do hereby declare the following to be a full, clear, and exact description of the invention, such as will enable others 10 skilled in the art to which it appertains to make and use the same.

This invention relates to new and useful improvements in valves and particularly to throttle valves used in connection with 15 steam engines, either of the stationary or locomotive type.

One object of the invention is to provide a valve of this character in which the valve head can be removed without danger of 20 escape of steam or hot water from the boiler, and the said valve rotated on its seat to grind the same to its seat.

Another object is to provide a valve of this character wherein are disposed two 25 valve heads each of which is unseated when the other is seated, by the seating action of the other.

Other objects and advantages will be apparent from the following description when 30 taken in connection with the accompanying drawing.

In the drawing:

Figure 1 is a side elevation of a valve made in accordance with the invention.

Figure 2 is a vertical longitudinal central 35 sectional view through the valve casing, the valve heads being shown in elevation, the valve being shown in open position, for draining purposes.

Figure 3 is a view similar to that of Figure 2, but showing the valve operating stem removed, and the valve in position for grinding.

Figure 4 is a vertical transverse sectional 40 view taken on the line 4—4 of Figure 2.

Figure 5 is a vertical transverse sectional 45 view taken on the line 5—5 of Figure 2.

Referring particularly to the accompanying drawing, 10 represents the valve casing 50 in which is formed the chamber 11, adjacent one end. Extending from one end of this chamber, through the adjacent end of the casing, is a threaded bore 12, in which is screwed the threaded operating 55 stem 13, of the valve. The outer end of

this stem is provided with the usual hand wheel 14.

In the inner end of the chamber 11 there is formed a conical seat 15, and extending from the inner end of this seat to a point 60 adjacent the other end of the casing, is a small bore 16, the same terminating at said other end of the casing, in the inner end of a similar conical valve seat 17. The outer or wider end of the latter seat 17 is extended through the end of the casing in an internally threaded bore 18 in which is received the removable and centrally apertured plug or cap 19.

The inner end of the operating stem 13 70 is formed with a central longitudinal cavity 13', as clearly seen in the sectional view Figure 2, wherein the inner end of the said stem is partially broken away.

Disposed on the seat 15 is a valve head 75 20 which is termed the gauge valve having a rearwardly extending stem 21 which enters the cavity 13' of the operating stem 13. Screwed into the other or smaller end of the valve head 20 is a stem 22 which extends 80 longitudinally in the bore 16. Disposed against the seat 17 is a similar valve head 23 which is termed the check valve, having a rearwardly extending stem 24, and having the short stem 25 which extends into the 85 bore 16 toward and into contact with the adjacent end of the stem 22 of the valve head 20. The depth of the cavity 13' is such that when the stem 13 is screwed into the casing to its full extent, the end of the 90 stem 21 will engage with the inner end of the cavity and the valve 20 be thus driven against the seat 15. At the same time the stem 22 will engage the stem 25 and push the valve 23 from its seat. The relative 95 lengths of the stems 22 and 25 are such that both valves may be unseated at the same time, and when the stem 13 is turned outwardly, the pressure from within the boiler (not shown) will operate to force the valve 100 23 against its seat, with the result that its stem 25 will push the stem 22, and force the valve 20 from its seat, the stem 21 sliding into the cavity 13'.

Formed on one side of the portion of 105 the casing 10 in which is formed the chamber 11, is a discharge nipple 26.

When the stem 13 is completely removed from the casing, the valve 23 will be firmly seated against the seat 17, while the valve 110

20 will be driven completely away from its seat 15. The valve 20, is then removed from the casing, and the stem 22 unscrewed from the valve. The valve 20 is then re-
5 stored to its seat 15, after which a screw driver (not shown) may be engaged in the notch 21' of the stem 21, and the valve rotated back and forth against the seat 15, until the valve and seat are properly ground.
10 This arrangement is clearly seen in Figure 3. When the valve 20 is removed the pressure of the boiler holds the valve 23 tightly against the seat 17, so that danger of escap-
ing water or steam is effectively prevented.
15 By reference to Figures 4 and 5, it will be seen that the cross sectional area of the portion of the bore 16 which is unoccupied by the stems 22 and 25, is greater than the cross sectional area of the opening between
20 the seat 15 and the valve head 20, when said valve is completely unseated. This provides a constricted space between the valve head and its seat which will be kept clear of any accumulations of mud, or sedi-

ment, by the force exerted by the water or steam flowing through the larger area of the bore.

What is claimed is:

A gauge cock having its casing provided with oppositely disposed inner and outer 20 valve seats, oppositely seating check and gauge valves for said seats and provided with positioning stems terminally contacting to provide a selective seating of the valves, the gauge valve having an outwardly directed regrinding stem and having its 35 positioning stem detachably secured thereto, and a valve operating stem having an inner terminal bore for receiving the regrinding stem of the gauge valve for swivel 40 engagement therewith.

In testimony whereof, I affix my signature, in the presence of two witnesses.

SAMUEL T. McLELLAN.

Witnesses:

CLAUDE L. SMITH,
SHIRLEY BRADFORD.
